PRODUCE COOLING PROCESS

Ellis H. Spiegl, Salinas, Calif.

Application July 19, 1947, Serial No. 762,149

9 Claims. (Cl. 99—193)

1

My invention relates to means for cooling produce preparatory to shipment and is especially concerned with a process for removing the field heat from produce such as lettuce prior to its shipment to market.

Lettuce is customarily harvested in the field at a relatively elevated temperature and is ultimately shipped by refrigerator car transcontinentally to market. Although a refrigerator car is well insulated and is also often supplied with ice or other refrigerant enroute, it is desirable that the field heat in the lettuce first be removed as promptly as possible in order to enhance the keeping qualities of the lettuce. Often crushed water ice has been packed in the lettuce crates and as a blanket over the lading of crated lettuce in a refrigerator car, but there has been a severe disadvantage in that the sharp corners and spikes on the crushed ice perforate the lettuce leaves permitting the latex to ooze out and oxidize. This necessitates upon arrival at market the removal of the outer several layers of the lettuce head thereby reducing its size and depreciating its market value.

At least in part to overcome this difficulty, I devised sometime since a process for making a refrigerant or coolant in the nature of a relatively light brine; that is, water containing some salt, and likewise containing frozen beads of soft, crystalline, snow-like conformations which were not sharp to the touch and did not bruise the lettuce leaves. This type of material particularly the solids, is sometimes called "snow-ice" and is referred to for example in my Patent Number 2,299,414 issued October 20, 1942.

The standard scheme of shipment has heretofore entailed the use of the snow-ice portion of the refrigerant packed into the lettuce crates intimately with the layers of lettuce heads and then finally, as a blanket layer, over crates or packages of lettuce after they have been installed in a refrigerator car.

While, in general, the scheme has been reasonably satisfactory, it is an object of this invention to improve the cooling process.

Another object of my invention is to provide a means for reducing the amount of refrigerant necessary in shipment of lettuce to market.

Another object of the invention is to provide a process for preparing lettuce for market in which the lettuce will arrive in a substantially undeteriorated condition.

Another object of the invention is to provide a means for quickly removing the field heat from lettuce or comparable produce.

2

Other objects of the invention, together with the foregoing are attained by the practice of my process as exemplified herein. The usually attendant mechanism is illustrated diagrammatically in the accompanying drawing in which

The figure shows a refrigerator car in cross section being supplied with snow-ice and light brine from a schematically represented source.

While the process has been largely successful with lettuce, and is so described herein, it can equally well be applied to other produce in which similar requirements are posed and in which similar treatment is beneficial.

In carrying out the practice of my process the lettuce heads are picked in the field in the customary fashion and have a field temperature of a substantial amount, for example in the neighborhood of 80 to 90 degrees Fahrenheit.

The lettuce heads 6 are packed directly into containers 7 such as crates made up of slats 8 so that there is adequate air circulation around the lettuce heads within the packed containers. These, contrary to normal practice, are originally packed without any ice or other solid refrigerant of any character within the containers.

The previous containers packed with lettuce heads are then disposed in suitable arrangement for free circulation within a standard refrigerator car 9. The car itself is thermally well insulated and is normally provided with ice bunkers 11 and 12 for the reception of solid ice refrigerant to maintain a low temperature within the car during transit.

In accordance with my process, the packed lettuce containers 7 are disposed in the car on the normal slat floor 13 thereof so that there is free air circulation throughout the lading. The produce is then cooled and the field heat is substantially removed therefrom by pumping or otherwise providing or discharging within the car a coolant, preferably comprising a light brine and snow-ice made in accordance with my mentioned patent. This fluid material is pumped from a container 14 through a flexible hose line

16 so that the coolant is distributed over the top of the lading. The cold liquid, approximately at 32 degrees Fahrenheit, and the snow-ice particles drain or sluice down over the containers and through the previous sides thereof and in between the lettuce leaves and heads to come into intimate contact with the lettuce to extract the heat therefrom.

Some of the snow-ice is in this process melted and it, together with the remaining liquid, drains through the floor of the refrigerator car and out

the drain pipe 17 thereof. The solid snow-ice 18 remains behind in the refrigerator car and especially in and on the lettuce heads 6 within the containers 7 so that a relatively uniform distribution of coolant is effectuated throughout the lading. The deposited snow-ice remains with the lading until it melts or is removed from the car. The discharged liquid coolant flowing from the drain pipe 17 is either wasted if its temperature has been raised to approximately atmospheric temperature, or if desired, it is returned through an appropriate conduit 19 to the snow-ice manufacturing equipment for remanufacture into further coolant.

While it has been customary to cool lettuce prior to packing it in refrigerator cars, and while it has been customary to cool produce by circulating air in refrigerator cars after the produce has been stored therein, so far as I know, it is new to sluice a liquid coolant especially a light brine carrying solid snow-ice particles over packed produce within the refrigerator car prior to shipment. When this liquid heat extraction step has been carried to a point so that the field heat is substantially removed from the produce, the flexible hose 16 or other distributing equipment is removed from the refrigerator car. The car doors are closed or sealed so that the then cooled produce is contained entirely within an insulated chamber supplied with refrigerant from the bunkers, if necessary, and is then shipped to its destination. Experience indicates that produce prepared in this fashion arrives at the market in excellent condition and with substantially no exterior leaf damage so that it is readily salable.

• I claim:

1. A produce cooling process comprising packing the produce in containers pervious to coolant, disposing the packed containers in a thermally insulated chamber having a liquid outlet, discharging a coolant in the form of snow-ice in a light brine vehicle over said containers, removing the liquid portion of said coolant from said chamber and leaving the solid portion of said coolant in said chamber.

2. A produce cooling process comprising packing the produce in containers pervious to coolant, disposing the packed containers in a thermally insulated chamber having a liquid outlet, supplying a coolant in the form of snow-ice in a light brine vehicle to said containers to filter therethrough by gravity, and removing the liquid portion of said coolant from said chamber.

3. A produce cooling process comprising packing the produce in containers pervious to coolant, disposing the packed containers in a thermally insulated chamber having a liquid outlet, supplying a mixed liquid and solid coolant to said chamber to filter through said containers by gravity, removing spent liquid coolant from said chamber, thereby leaving solid coolant therein and recirculating said liquid coolant with solid coolant added.

4. A produce cooling process comprising disposing produce in a thermally insulated chamber having a liquid outlet, discharging a coolant in the form of snow-ice in a light brine vehicle over said produce to filter therethrough by gravity, removing the liquid portion of said coolant from said chamber, and leaving the solid portion of said coolant in said chamber.

5. A produce cooling process comprising packing the produce in containers pervious to coolant, disposing the packed containers in a refrigerator car, discharging a coolant in the form of snow-ice in a light brine vehicle over said containers in said car to filter therethrough by gravity, and draining the liquid portion of said coolant from said car.

10 6. A produce cooling process comprising disposing produce containing field heat in a refrigerator car, discharging a coolant in the form of snow-ice in a liquid vehicle over said produce until the field heat has been substantially removed therefrom, draining the liquid portion of said coolant from said car, and sealing said car.

20 7. A produce cooling process comprising disposing produce containing field heat in a refrigerator car, discharging a coolant in the form of snow-ice in a cold liquid and solid mixture over said produce until the field heat has been substantially removed therefrom, removing the liquid portion of said coolant from said car, discontinuing said discharge, and then sealing said car.

25 8. A lettuce cooling process comprising packing the lettuce containing field heat in containers pervious to coolant, disposing said packed lettuce in a refrigerator car, discharging a coolant in the form of snow-ice in a vehicle of light brine over said packed lettuce until the field heat is substantially removed therefrom, draining the liquid portion of said coolant from said car, and closing said car for shipment.

30 9. A produce cooling process comprising packing produce containing field heat in containers pervious to coolant, disposing the packed containers in a thermally insulated chamber, discharging a coolant in the form of snow-ice in a liquid vehicle over the packed containers until the field heat has been substantially removed from the produce, said packed containers retaining snow-ice within said chamber, removing the remaining liquid portion of said coolant from said chamber, and remanufacturing said removed liquid portion into further coolant.
